UNITED STATES PATENT OFFICE.

EDWARD C. PERRY AND FRANK D. PERRY, OF WORCESTER, MASSACHUSETTS, ASSIGNEES TO AMERICAN CAR SPRINKLER CO., OF WORCESTER, MASSACHUSETTS, A CORPORATION OF MASSACHUSETTS.

MACHINE FOR APPLYING BITUMINOUS MATERIALS AND THE LIKE TO ROADS.

1,113,139.

Specification of Letters Patent.

Patented Oct. 6, 1914.

Application filed July 3, 1912. Serial No. 707,509.

To all whom it may concern:

Be it known that we, EDWARD C. PERRY and FRANK D. PERRY, citizens of the United States, both residing at Worcester, in the 5 county of Worcester and State of Massachusetts, have invented a new and useful Machine for Applying Bituminous Materials and the like to Roads, of which the following is a specification.

10 This invention relates to a machine for distributing bituminous or other road surfacing material, particularly heavy asphalt oils. Oils of this character are those containing above 60 or 65% asphalt. It is so 15 difficult to melt these oils and reduce them to such a condition of fluidity as to make them flow easily for the purpose of applying them to roadways that heretofore, so far as we are aware, in the practical manip- 20 ulation of this class of road-surfacing materials, it has been considered necessary to use a very cumbrous and expensive device for this purpose involving a road roller capable of producing steam in large 25 amounts, a tank vehicle trailing behind it, and a third vehicle constituting a trailer for distributing the oil from the tank vehicle. This forms a long train which cannot turn in ordinary roadways and which cannot 30 work to advantage on anything except the longest stretches of roads. In addition to this even with that apparatus, it has not been found an easy matter to spray the road-surfacing material under all condi- 35 tions, and constant vigilance has been necessary in order to keep the material in proper condition for application to the roads.

The principal objects of this invention are 40 to provide for melting and distributing these heavy oils by improved apparatus mounted on a single vehicle so as to avoid the cumbrous train of vehicles above described and it is a further object to provide 45 an apparatus by which the oils, even of the heaviest type, can be reduced to a proper condition for spraying on the roadway in a minimum of time and kept in that condition as long as may be desired.

Further objects of the invention are to provide a machine of this character of the self-propelled type in which all the elements are conveniently assembled on a single frame so as to move along the road to-

gether; to provide power operated means 55 adapted to be operated by the motor which drives the machine for drawing the road surfacing material from a tank and supplying it directly to spraying nozzles; to provide regulatable means whereby the pressure of the material at the nozzles can be varied to suit different conditions without changing the speed of the motor or the pump which forces the material through the nozzles and at the same time to provide for 60 the filling of the tank by the use of the same connections in part at least.

The invention also involves the combination with these elements of a steam-making device carried by the truck and adapted to 70 heat the material in the tank to a high temperature and with such efficiency that the spray pipe will not have to be heated, and means whereby the exhaust steam can be used for reheating the material that is 75 forced past the nozzles and back into the tank.

The invention also involves other features of construction as will appear hereinafter.

Reference is to be had to the accompanying drawings in which—

Figure 1 is a side elevation of a machine constructed in accordance with this invention; Fig. 2 is a rear elevation of the tank 85 thereof and pump with the connections between them; Fig. 3 is a sectional plan near the bottom of the tank showing the heating coil; and Fig. 4 is a plan of certain portions of the mechanism for connecting the 90 motor with the pump.

The invention is shown as applied to a truck or vehicle 10 provided with a motor located in a casing 11 near the front and having also an auxiliary engine or motor 95 12. On the frame just behind the auxiliary motor is a tank 13 for the road surfacing material adjacent to which is a water tank 14. The driving shaft 15 of the main motor is provided with a longitudinally 100 slideable pinion 16 adapted when in one position to mesh with a gear 17 on a shaft 18 which by means of gearing 19 drives a shaft 20 which is connected with and operates the pump 21. On the shaft 18 also is a 105 sprocket wheel 22 adapted to be driven by a chain 23 from the shaft 24 of the auxiliary engine 12. The pinion 16 on the main

driving shaft of the motor is operated by a link 26 connected with an operating lever 27. In ordinary operation the lever 27 is moved to the position shown in the drawings, which brings the pinion 16 out of mesh with the gear 17. The shaft 15 drives the driving wheels in any of the ordinary ways. When it is desired to operate the pump 21, this can be done either by shifting the pinion 16 into mesh with the gear 17 by means of the lever 27, or by starting up the auxiliary engine 12.

The tank 13 for the road surfacing material is connected with, and supports, the pump 21 by means of a short pipe 30 having a valve 31 by which it can be closed. The outlet 32 from the pump is connected directly with a horizontal pipe 33 which is provided with spray nozzles 34 of any desired character. It will be seen, therefore, that with the valve 31 open and the pump in operation the material will be positively forced into the spray pipe 33. The pump preferably is designed to be capable of a higher duty than that for which it is usually required, and it is designed to serve another purpose besides that of supplying the spray pipe, that is, it is provided with a by-pass 35 from its outlet back into the tank through a pipe 36. This results in the circulation of the liquid and also permits the regulation of the pressure at the nozzles. This regulation is secured by means of a regulating valve 37. When it is desired to increase the pressure at the nozzles, this valve is adjusted to reduce the opening therethrough, and vice versa. Another by-pass 38 is provided having a cut out 39 therein so that fresh liquid can be introduced from the by-pass 35 through a connection 40 simply by opening the valve 39 without disturbing any adjustment of the valve 37.

At the rear of the tank 10 is shown a gas furnace 42 supplied with gas from a tank 43 and with water from the tank 14 by connections not shown herein. This furnace is of a type capable of generating a high temperature and producing superheated steam consequently at a high pressure. The steam 50 is discharged through a pipe 44 into a coil or series of pipes 45 in the bottom of the tank 13. The exhaust is taken out through a pipe 46 which is connected by a pipe 47 with a pipe 48 inside the by-pass 35 and extending 55 from end to end thereof practically for the purpose of heating the liquid which circulates therethrough. This exhaust steam is discharged through a cock 49. The exhaust pipe 46 is also connected with a pipe 50 which passes into the spray pipe 33. That portion of the pipe 50 lying within the pipe 33 is provided with perforations and that portion exterior to the pipe 33 is provided with a valve 51, this construction permitting 60 the spray pipe 33 and also the by-pass 35 to

be cleaned out by the force of the exhaust steam. It will be understood, of course, that the coils 45 are located within the tank where they come into contact with the material to be kept in molten condition, and that any desired kind of splash plates 53 can be employed in the receptacle. When the steam, whether exhaust or live, is turned into the pipe 48, it keeps the oil in the pipe 35 in a thoroughly molten condition, and the steam passing down through the pipe 50 is forced into the pipe 33 and clears it out. But if the valves 49 and 51 are closed, all the steam has to pass up through the valve 37. Then part of it passes through the valve 39 and pipe 38 and into the pipe 35. This will assist in clearing out the spray pipe. But if the nozzles and valves 49 and 51 are closed in the first place, this steam has to pass into the steam exhaust of the pump and it turns the rotary pump backward and draws the molten material out of the spray pipe back into the tank. This tank is shown as provided with an inlet tube 54 having a cap for closing the same and with a tube 55 provided also with a cap and used for inspection only.

With this construction it has been found in practice that the range and efficiency of the road surfacing machine are very materially increased. While the machine is on the way to the place at which it is to be used, steam can be in the process of being generated so that it can start out on a job without any material preparations and it can be used for long stretches of road, its period of usefulness being limited only by the capacity of the tank and by the distance away of the source of supply of the road surfacing material.

While we have illustrated and described a preferred embodiment of the invention, we are aware of the fact that modifications can be made therein, and the principles of the invention carried out in other forms without departing from the scope of the invention as expressed in the claims. Therefore we do not wish to be limited to all the details of construction herein shown and described, but

What we do claim is:—

1. An apparatus for heating and spraying heavy oils having, in combination, a wheel truck, a tank mounted thereon having a bottom slanting from the front to the rear and having a steam coil located therein, means mounted on the truck for producing superheated steam, means for conducting the superheated steam directly to said steam coil, a pump located directly under the rear end of the tank, a short pipe for conducting oil from the lowest point of the tank directly to said pump, a spray pipe below and closely adjacent to said pump, and a connection for conducting the oil under pressure from the

pump directly to the spray pipe, said spray pipe extending transversely of the truck in the rear of the wheels.

2. An apparatus for heating and spraying heavy oils having, in combination, a wheel truck, a tank mounted thereon and having a steam coil therein, means mounted on the truck and connected to said steam coil for supplying steam thereto, a short connection extending downward from the bottom of the tank at the rear thereof, a pump supported by said connection and receiving said connection as its intake, and a spray pipe connected with the pump and located below and closely adjacent thereto, said spray pipe extending transversely of the truck in the rear of the wheels.

3. An apparatus for heating and spraying heavy oils having, in combination, a wheel truck, a tank mounted thereon having an outlet in the bottom thereof, means mounted on said truck for heating the oil in said tank to a high temperature, a pump located below and closely adjacent to said outlet, a short pipe extending downward from the bottom of said tank and connecting said outlet to said pump, a spray pipe located below and closely adjacent to said pump and extending transversely of said truck in the rear of the wheels, and a short direct connection between said pump and said spray pipe for conducting the heated oil under pressure from said pump to said spray pipe.

4. In an apparatus for spraying heavy oils, the combination of a tank having a bottom slanting down toward the rear, a steam coil located along the bottom of said tank, means mounted at the rear of said tank and movable therewith for producing superheated steam, a pipe extending from the superheating means to the front end of the steam coil, a straight vertical connection extending from the lowest part of the bottom

of the tank at the rear, a pump supported by said vertical connection and receiving said connection as its intake, means at the front of the tank for propelling the vehicle and operating the pump, and a spray pipe directly connected with the pump.

5. In a machine of the class described, the combination, with a vehicle frame, of a tank on the frame for road surfacing material, a series of spray nozzles below the frame, a pump on the frame between the tank and nozzles and connected therewith, means for connecting the connection between the pump and nozzles with the top of the tank, and means for heating said connecting means and directing steam through the pump backward to draw the surfacing material from the spray nozzles back into the tank.

6. In a machine of the class described, the combination with a vehicle frame, of a tank thereon for road surfacing material having steam pipes therein, a gas heater on the frame just behind said tank and having means for supplying steam to said pipes, a pump below the tank and connected therewith, a spray pipe below the pump, a connection between the pump and spray pipe, a by-pass from said connection to the top of the tank, and an exhaust pipe from said steam pipes passing through said by-pass lengthwise and having a connection extending into the spray pipe whereby the spray pipe and by-pass can be cleaned out by exhaust steam.

In testimony whereof we have hereunto set our hands, in the presence of two subscribing witnesses.
